UNITED STATES PATENT OFFICE.

WILLIAM LIDDELL, OF NEW YORK, N. Y., ASSIGNEE, BY MESNE ASSIGNMENTS, TO
SIMPLEX BAG COMPANY OF LONG ISLAND CITY, A CORPORATION OF NEW YORK.

PAPER-BAG MACHINE.

943,428.

Specification of Letters Patent. Patented Dec. 14, 1909.

Application filed June 15, 1908. Serial No. 438,497.

To all whom it may concern:

Be it known that I, WILLIAM LIDDELL, a citizen of the United States, and resident of the borough of Brooklyn, county of Kings, city and State of New York, have made certain new and useful Inventions Relating to Paper-Bag Machines, of which the following is a specification, taken in connection with the accompanying drawings.

10 This invention relates to paper bag machines and relates especially to mechanism for forming satchel bottom paper bags from the bellows folded bag tubes, the bags being preferably clamped and held upon a rotary carrier having a number of sets of clamping devices for that purpose so as to carry the bags past a number of opening and forming devices arranged at different stations around the carrier to successively act upon the bags, 20 a suitable opener roll, deflectors, a swinging folder and folder roll, an indenter, a pastier and closer being employed in this way, if desired, before the bags are released from the carrier and engaged by suitable delivery mechanism in which the bottoms may be closed and sealed in proper position.

In the accompanying drawings showing an illustrative embodiment of this invention and in which the same reference numeral refers to similar parts in the several figures, 30 Figure 1 is a longitudinal sectional view. Fig. 2 is a plan view. Figs. 3 and 4 are enlarged partial longitudinal sectional views showing the mechanism in different positions. Fig. 5 is an enlarged transverse view showing the deflectors and folders. Fig. 6 is an enlarged partial transverse section showing the clips and operating mechanism. Fig. 7 is a similar view showing the tuckers 40 and their auxiliary devices. Fig. 8 is an enlarged side view showing parts of the folder operating mechanism. Fig. 9 is a plan view of the completed bag, parts being broken away.

45 In the illustrative embodiment of the invention shown in the drawings the previously formed and pasted bag tube is regularly supplied in severed lengths 116 to the feed plate 5 mounted on the bracket 6 and is fed by the coöperating feed rolls 3, 4 over the sectional guide 8 which is curved to deliver the bag to the opener roll 1 and carrier drum 2. The sectional guide 8 may as indicated be mounted on the bracket 6 and lie in

suitable grooves or channels in the lower 55 feed roll 3 so as to form in connection therewith a substantially flat surface with which the upper feed roll coöperates. The leading edges or lips of the bag tube are engaged by the double gripper 30 in the carrier drum 60 and by the gripper 21 in the opener roll, it being understood that any desired number of equally spaced sets of grippers and other clamping devices may be mounted on the carrier drum according to its size, four sets 65 of such mechanism being illustrated in the drawings.

The opening and forming devices arranged at the several stations to coöperate with the carrier are of course so arranged 70 and operated as to complete their cycles of operation in the time required for the carrier to move the distance between two successive sets of clamping devices. The opener roll 1, for instance, is shown as having one- 75 fourth the diameter of the carrier and since moving at the same surface speed makes one complete revolution during a quarter revolution of the carrier which is the distance between the corresponding clamping devices 80 of two adjacent sets. The folder roll 72 is half the diameter of the opener roll so that it makes two complete revolutions for each quarter turn of the carrier, always being in proper phase therewith so as to bring the 85 slot 147 into engagement with the proper part of the bag.

The gripper 21 may be mounted on the gripper rod 158 in the opener roll and be normally held in closed position by the 90 gripper spring 157 engaging a suitable extension 23 on one end of the gripper rod as indicated in Fig. 3. The gripper arm 22 may be mounted on the other end of this rod so as to coöperate at the proper time with a 95 suitable gripper cam, such as 153, to rotate the gripper rod and open the gripper for engagement with the upper or rear flap or lip of the bag, and then when the arm moves out of contact with the cam the gripper is brought down against the roll clamping the bag lip thereto with the desired pressure. The further rotation of the roll 100 brings the arm 22 into engagement with the releasing cam, 109, to open the gripper and 105 release the rear flap of the bag. The double grippers 30 may be suitably spaced apart and mounted on the gripper rod 120 in the

periphery of the carrier drum, this rod carrying the gripper arms 31 coöperating in a similar way with suitable cams 110, 164 to open the gripper to engage and disengage the front flap of the bag, it being understood of course that the double grippers 30 mounted on the carrier drum engage the front flap on either side of the gripper 21 mounted on the opener roll which may engage the bag lip shortly after the double gripper engages.

The tuckers 20 may be mounted on suitable tucker rods 153 mounted on the sides of the opener roll and engaged by the tucker springs 25 normally tending to swing the rods and tuckers inward into operative position. The tucker arm 26 is mounted on the tucker rod as indicated and when engaged by a suitable stationary cam in the path of the arm, such as 187, retracts the tucker and holds it in retracted position so long as the cam engages the arm. Suitable lifters 155 may be rigidly mounted on the lifter rod 156 extending through the opener roll so as to engage the lugs 154 on the tucker rods and simultaneously lift the tuckers into their operative position beyond the tread of the opener roll, as indicated in Fig. 3 when the pin or roll 119 on the extension 18 of one of these lifters is engaged by the stationary cam 19, the tuckers being at other times normally retracted within or substantially coincident with the roll tread by the springs 25. The carrier tuckers 28 may be mounted in pairs on the carrier drum in a generally similar way, these tuckers as indicated in Fig. 7 being mounted on the tucker rods 34 revolvably supported in bearings 46 on the sides of the drum and being normally withdrawn below or substantially coincident with the drum tread by the tucker springs 36. These springs also have a torsional action on the tucker rods and tuckers tending to rotate them into their operative angular position. Each pair of tuckers and rods rotate simultaneously since the cranks 45 on the rods are connected by the diagonally arranged pivoted tucker link 44 which swings the tuckers simultaneously inward. The rods may also be provided with the lugs 35 engaged by the lifters 38 rigidly mounted on the lifter rod 121 so as to be simultaneously operated when the roll 39 on the extension 37 of one of these lifters engages the stationary cam 40, as indicated in Fig. 1. At such times these lifters elevate the tuckers 28 above the drum tread and the tucker arm 29 thereupon coming into engagement with the tucker cam 84 as indicated in Fig. 7 the tuckers are swung inward into engagement with the bottom edge of the side fold and when the lifter roll moves out of engagement with the cam 40 the tucker springs 36 draw the tuckers down into firm engagement with this part

of the bag bottom, holding it in firm engagement with the drum as the tuckers 20 also do at this time, as indicated in Figs. 3 and 5, thus materially assisting in the formation of the diamond fold. By lifting the tuckers 28 considerably higher than their final clamping position before they are swung inward they engage the bag more reliably and definitely in spite of any slight lifting of this portion of the bag fold from the carrier drum. If desired, however, the aliners 113 carried by the aliner rods 85 mounted on either side of the drum and normally held in inoperative position by the aliner springs 114 which hold them against the stops 108 and 111 may be swung downward into momentary engagement with the bottom folds at about the time the tuckers engage the same by any desired means, such as the cams 86 on the shaft 59 which engage the aliner arms 87 mounted on the rods so as to swing the aliners down momentarily until the tuckers 28 come into engagement.

As the bag is fed forward and the primary transverse crease formed therein by the creaser 152 in the roll, its sides rise into engagement with the curved deflectors 10 mounted on a suitable bracket or support 9 and which may be formed as indicated in Fig. 5 so as to engage either side of the advancing bag bottom near the center and deflect the same inward to start the diamond fold. The diamond fold may be completed in any desired manner as by bringing a suitable folder into engagement with the bag bottom. The oscillating sectional folder plate 11 for this purpose may be mounted on the folder rod 12 by a suitable connector piece 13, this folder preferably having a projecting flange 151 on either side to engage and guide the sides of the diamond fold and promote the regular formation thereof. As shown in Fig. 5 the deflectors may be carried through the folder which may be formed with suitable apertures large enough to allow the desired movement of the folder without interference from the deflectors.

The folder and rod 12 may be normally held in lowered position by the spiral spring 92 shown in Fig. 2 as coöperating with the frame and with a suitable lug 91 on the rod, and the arm 93 on this folder rod coöperates with a suitable stop 165 on the frame to limit the downward movement of the folder so that its lower position may be suitably adjusted by adjusting the position of the arm 93 on the rod. In order to raise this folder at the proper time a suitable cam 88 may be mounted on the shaft 15 of the opener roll and the cam segment 90 pivoted about the pin 180 may be provided with the cam follower 89 to coöperate with this cam. The cam segment 90 as indicated in Fig. 8

meshes with the coöperating pinion 91 on the folder shaft so as to raise the folder at the proper time against the action of the spring 92. In this way the rod and connected sectional folder are brought down at the proper time into the position indicated in Fig. 4 so as to engage the bag bottom and form the diamond fold therein, the tuckers 20 and gripper 21 being released at about this time and the bag being carried forward by the carrier drum 2. The bag bottom is in this manner drawn under the folder and beneath the folding roll 72 which may be yieldably mounted at a suitable station adjacent the folder to coöperate with the carrier drum and exert the desired pressure on the bag by being mounted in bearing slots on either side of the frame so that its weight constantly presses the bag bottom downward, a suitable slot 147 being preferably formed in this roll to straddle the mid-seam of the bag bottom.

The paster 58 upon the paster shaft 59 may be mounted at a succeeding station and may have the desired shape to apply paste to the bag bottom, the indenters 56, 57 being also mounted on this paster so as to indent and crease the bag bottom and form the front flap 117 and the rear flap 118, the bag bottom being at this time clamped and held against the carrier drum by the clips 42. These clips, as indicated in Figs. 3, 4 and 6, may consist of resilient sheet metal secured to the outer ends of the clip arms 142, 143 loosely mounted on the studs 120 in the drum. These clips and arms are oscillated in unison by the connecting clip link 43 pivoted thereto so that the two clips move inward together when the clip roll 41 on the extension 141 of the arm 142 rides up on the stationary cam 71, this action taking place at substantially the same time that the indenter 57 engages the bag and holds it closely against the drum as indicated in Fig. 1, these clips constituting together with the gripper and carrier tuckers the clamping devices mounted on the carrier to hold the bags thereto. The paster may be supplied with paste in any desired way from the paste tank 47 in which the paste roll 49 rotates in engagement with a suitable doctor 48. The paste feeder 58 may be mounted on the rotating shaft 51 and carry the two similar feeding segments 53 provided with transverse portions 54 to coöperate with the similar transverse portion 55 on the paster and supply paste thereto, suitable recesses 52 being also formed in the feeder to accommodate the indentors 56, 67 on the paster.

60 A suitable closer is preferably mounted at a succeeding station to close the bag flaps against the bottom and the swinging and oscillating closer 60 may be used for this purpose. This closer which may be in the form of a suitable blade is secured to the

closer pivot 148 in the closer arm 64 mounted on the closer shaft 65 in the frame. The lever 149 on the closer pivot 148 carries a suitable roll 61 in engagement with the stationary cam 62, the closer spring 63 connecting the lever 149 and arm 64 so as to hold the roll and cam in engagement. As is indicated in Fig. 2, the closer shaft 65 is mounted in the frame and may be provided with the torsional spring 105 acting between the frame and the adjustable collar 104 on the shaft, thus tending to normally hold the closer in raised position. The crank 66 on this shaft is pivoted to the link 67 which is also pivoted to the outer end of the cam lever 68 whose lower end 166 is pivoted to the frame. The cam roll 69 on this lever coöperates with the cam 70 on the paster shaft 59 so as to swing the closer shaft 65 and closer while at the same time the closer is oscillated as described about its pivot 148 so that this closer blade travels quite close to the drum tread and the delivery guide 73 as the closer moves downward. In the position indicated in Fig. 1 the closer has moved upward engaging the front flap 117 and raising the same further out of contact with the drum so that this front flap is subsequently engaged by the closer roll 74 and forced backward into contact with the bag bottom. At this time the bag bottom has of course been fed over the delivery guide 73 mounted on the support 83 on the frame and begins to pass between the closer roll 74 and the coöperating roll 167 which operate to firmly press the pasted parts together and seal the same. At this time the closer 60 moves downward, engaging the rear flap 118 of the bag and throwing it forward into close engagement with the bag bottom which at about this time is released by the clips and fed forward under the closer roll. As indicated this closer roll may be movably mounted by supporting its pivot 112 in the swinging arms 76 mounted on the shaft 75 in the frame so as to yieldingly press the bag bottom together to the desired extent. Suitable feeding tapes which may be in the form of spiral springs 213 may extend around the closer roll 74 and delivery roll 77 and another series of feeding tapes 82 may extend around this delivery roll and the roll 80 passing around the periphery of the delivery drum 79 as indicated. This arrangement serves to hold the pasted bag bottom in sealed position until the paste has set sufficiently to permanently hold the parts together in proper position.

The parts are of course suitably mounted in a heavy supporting frame and the rolls and drums are preferably operated in unison by suitable gearing. All the drums and rolls engaging the bag are of course operated at substantially the same surface speed. The machine may be driven from the shaft

146 of the carrier drum upon which the main gear 98 may be mounted, this gear meshing with the gear 97 secured to the shaft 15 of the opener roll 1, with the gear 99 operating the folder roll and with the gear 100 secured to the shaft 59 of the paster. The closer roll 74 may if desired be geared to the coöperating roll 167 by the gears 106, 107 on the shafts 112 and 176 respectively, as indicated in Fig. 2. The gear 177 which is also secured on the shaft 176 as indicated in Fig. 1 meshes with a similar gear 101 above it which is in mesh with the main gear 98 to drive these rolls. The delivery drum 79 may be operated by the gear 103 on the shaft 81 of this drum which as indicated in Fig. 2 meshes with the intermediate gear 102 which is in engagement with the main gear 98. The paste-feeding devices may be operated in any desired way as by providing the feeder 58 with the gear 178 engaging the paster gear 100, the shaft 50 of the paste roll 49 carrying the gear 179 in mesh with this gear 178, as indicated in Fig. 1.

Having described this invention in connection with an illustrative embodiment thereof, to the details of which disclosure the invention is not of course to be limited, what is claimed as new and what is desired to be secured by Letters Patent is set forth in the appended claims.

1. In bag machines, a carrier drum, a plurality of spaced sets of clamping and forming devices mounted on said carrier, said devices comprising a pivoted gripper to engage a bag lip, carrier tuckers to engage and form the side folds and clips to hold the folded bag upon said carrier, means to successively operate said devices as said carrier rotates past the several stations, an opener roll mounted to coöperate with said carrier at one of said stations, a pivoted gripper mounted on said opener roll to engage the bag lip and open the end of the bag and tuckers on said roll to enter the side folds of the bag substantially simultaneously with the carrier tuckers, aliners co-operating with said carrier to align and hold the bag folds adjacent said carrier and insure the coöperation of the carrier tuckers therewith, stationary deflector blades mounted adjacent said carrier and opener roll to engage and guide inward the opening sides of the bag, a pivoted sectional folder provided with edge flanges mounted adjacent said deflector and operating means to swing said folder intermittently downward to engage and form the diamond fold in the bag end, a folder roll mounted at another station to coöperate with said carrier and complete the diamond folds in bags held by said carrier, a rotating combined paster and indenter mounted at another station to coöperate with said carrier and paste and in-

dent the bags held thereby, means to supply paste to said paster, a swinging and oscillating closer mounted at another station to engage the flaps of bags held by said carrier and bend them downward toward the bag bottom and delivery and closer devices mounted at another station to coöperate with said carrier to receive the bags from said carrier and close and seal the pasted bottoms thereof.

2. In bag machines, a carrier drum, a plurality of spaced sets of clamping and forming devices mounted on said carrier, said devices comprising a gripper to engage a bag lip, carrier tuckers to engage the side folds of the bag and clips to hold the folded bag upon the carrier, means to successively operate said devices as said carrier rotates past the several stations, an opener roll mounted to coöperate with said carrier at one of said stations, a gripper mounted on said carrier roll to engage the bag lip and open the end of the bag and tuckers on said roll to enter the side folds of the bag, stationary deflector blades mounted adjacent said carrier and opener roll to engage and guide inward the opening sides of the bag, a pivoted sectional folder provided with edge flanges mounted adjacent said deflector and means to swing said folder downward to engage and form the diamond fold in the bag end, a folder roll mounted at an adjacent station to coöperate with said carrier and complete the diamond folds in the bags held by said carrier, a paster and indenter to coöperate with said carrier and paste and indent the bags held thereby, a closer to engage the flaps of bags held by said carrier and bend them downward toward the bag bottom and delivery and closer devices mounted to coöperate with said carrier to receive the bags therefrom and close and seal the bottoms thereof.

3. In bag machines, a moving carrier, a plurality of spaced sets of clamping and forming devices mounted on said carrier, said devices comprising a gripper to engage the bag lip, carrier tuckers to engage the side folds and clips to hold the folded bag upon said carrier, means to operate said devices as said carrier moves past the several stations, an opener mounted to coöperate with said carrier at one of said stations, a pivoted gripper mounted on said opener to engage the bag lip and open the end of the bag and tuckers on said opener to enter the side folds of the bag, defectors and a moving folder mounted adjacent said opener to engage and form the diamond folds in bags held by said carrier, a paster to coöperate with said carrier and paste the bags held thereby, a closer mounted at another station to engage the flaps of bags held by said carrier and delivery and closer devices mounted at another station to coöperate with

said carrier to receive the bags from said carrier and close and seal the pasted bottoms thereof.

4. In bag machines, a moving carrier, a plurality of spaced sets of clamping devices mounted on said carrier to hold the bags in engagement therewith as said carrier moves past the several stations, an opener mounted to coöperate with said carrier at one of said stations and open the end of the bag, stationary deflectors and a coöperating moving folder mounted adjacent said opener to engage and form the diamond fold in bags held by said carrier; a paster coöperating with said carrier to paste the bags held thereby and delivery and closer devices mounted to coöperate with said carrier to receive the bags therefrom and close the pasted bottoms thereof.

5. In bag machines, a moving carrier, a plurality of spaced sets of clamping devices mounted on said carrier to hold the bags in engagement therewith as said carrier moves past the several stations, an opener mounted to coöperate with said carrier at one of said stations and open the end of the bag, stationary deflecting means in the path of the bottoms of said opening bags to deflect the same inward, a coöperating moving folder to engage and form diamond folds in said opened bags and having edge flanges alining the lateral edges of the diamond fold and pasting and closing devices coöperating with said carrier.

6. In bag machines, a moving carrier, a plurality of spaced sets of clamping devices mounted on said carrier to hold the bags in engagement therewith as said carrier moves past the several stations, opening devices mounted to coöperate with said carrier and open the ends of the bags, stationary deflecting means engaging and inwardly deflecting the lateral edges of the opening bottoms of said bags and a folding plate to subsequently engage and form the diamond folds in said bags held by said carrier.

7. In bag machines, a moving carrier, a plurality of spaced sets of clamping devices mounted on said carrier to hold the bags in engagement therewith, opening devices coöperating with said carrier to open the ends of said bags, deflectors engaging and inwardly deflecting the sides of said opening bags in advance of said clamping devices and coöperating swinging folding means to engage and form diamond folds in said opened bags.

8. In bag machines, a moving carrier, a plurality of spaced sets of clamping devices mounted on said carrier to hold bags thereon, means to open the bottoms of bags held by said carrier, tuckers to engage the folds of said opening bag bottoms, means to engage and inwardly deflect the sides of said opening bag bottoms in advance of said

clamping devices and folding means to form diamond folds in said bag bottoms while held by said carrier and engaged by said tuckers.

9. In bag machines, a moving carrier, a plurality of spaced sets of clamping devices mounted on said carrier to hold bags in engagement therewith, opening devices to open the ends of bags on said carrier, deflector blades to engage and inwardly deflect the free lateral edges of said opening bags and a moving flanged folder engaging and forming diamond folds in the opened bags.

10. In bag machines, a moving carrier, clamping devices mounted on said carrier to hold bags in engagement therewith, opening devices to open the ends of bags held by said carrier, stationary deflector blades to engage and inwardly deflect the sides of said opening bags, and a moving folder enclosing said deflectors to engage and form diamond folds in the opened bag bottoms.

11. In bag machines, a moving carrier, a plurality of spaced sets of clamping devices mounted on said carrier to clamp bags thereto, an opener mounted at a station to coöperate with said carrier and open the bag ends, folding devices mounted adjacent said opener to engage the opened ends of bags held by said carrier and form the diamond folds therein, pasting and indenting means mounted at another station to coöperate with said carrier and paste and indent the bags held by said carrier and delivery and closer devices mounted at another station to coöperate with said carrier and receive and close the bags therefrom, said closer devices comprising stationary closer rolls and a swinging and oscillating closer moving closely adjacent the bag bottom to hold the rear flap in engagement therewith.

12. In bag machines, a rotating carrier having a fixed axis, clamping means on said carrier to clamp bags thereto and a swinging and oscillating closer coöperating with said carrier to engage the flaps of bags held thereon and move closely adjacent the bag bottoms to hold the rear flap in engagement therewith.

13. In bag machines, a carrier, means to hold bags in engagement therewith, a closer shaft, a closer arm mounted on said shaft to have swinging movement with respect to said carrier, a closer pivot in said arm, a closer mounted on said pivot, a closer lever secured to said closer and a closer cam to coöperate with said lever to oscillate said closer as it is swung by said shaft to carry said closer closely adjacent the bottom of the bag on said carrier and hold the bag flap in engagement therewith.

14. In bag machines, a carrier having a fixed axis, means to clamp a bag on said carrier, a guide coöperating with said carrier, a swinging closer arm, a closer pivoted to said

arm and carrying a closer lever, a cam co-operating with said lever to oscillate said closer as it swings to move said closer closely adjacent the bottom of a bag on said carrier and guide to close the bag flap against said bottom.

15. In bag machines, a carrier, means to clamp a bag upon said carrier, a guide co-operating with said carrier, a swinging closer arm, a closer pivoted to said arm, a closer lever secured to said closer and yieldingly connected with said closer arm and a cam co-operating with said closer lever to oscillate said closer as it is swung upon said arm to engage and close a bag flap against the bottom of the bag as it moves against the bag bottom on said closer and guide.

16. In bag machines, a carrier, means to hold bags upon said carrier, means to open the ends of said bags, deflector blades to engage and deflect inward the sides of said opening bag bottoms and a swinging folder plate provided with edge flanges and with apertures to accommodate said deflectors mounted adjacent said deflectors to engage and form the diamond folds in said opened bag ends.

17. In bag machines, means to open the bag bottoms, stationary deflectors to engage and inwardly deflect the sides of said opening bag bottoms and a moving folder plate having edge flanges and apertures to accommodate said deflectors to engage and form diamond folds in said opened bag bottoms.

18. In bag machines, means to open bag bottoms, deflector blades to engage and inwardly deflect the sides of the opening bag bottoms and a moving flanged folder engaging said deflectors to engage and form diamond folds in the opened bag bottoms.

19. In bag machines, means to open bag bottoms, means to engage and inwardly deflect the sides of said opening bag bottoms and a flanged folder to engage and form diamond folds in said opened bag bottoms.

20. In bag machines, a carrier, means to hold bags upon said carrier, means to open the ends of said bags, deflectors to engage the opening bag ends and a swinging folder plate provided with edge flanges mounted adjacent said deflectors to engage and form the diamond folds in said opened bag ends.

21. In bag machines, means to open bag bottoms and hold the same in extended position, a folder and means to move said folder into contact with said extended bag bottoms in a direction substantially transverse to the plane of said bag bottoms to form diamond folds therein, said folder having an edge flange to engage and aline a lateral edge of the diagonal folds in said bag bottoms.

22. In bag machines, a moving carrier, means to open and extend the bottoms of bags engaged by said carrier and a folder swinging about an axis substantially parallel to the axis of rotation

to the axis of said carrier to engage and form diamond folds in said extended bag bottoms, said folder having edge flanges to engage and aline the lateral edges of the diamond folds.

23. In bag machines, a moving carrier, a plurality of spaced sets of clamping devices mounted on said carrier to engage and hold bags thereon, means to open the bottoms of said bags, a flanged folder to engage and form diamond folds in the said opened bottoms of bags held by said carrier and a folder roll to subsequently engage said folded bag bottoms.

24. In bag machines, a moving carrier, a plurality of spaced sets of clamping devices mounted on said carrier to hold bags, means to open the bottoms of bags held by said carrier and tuckers to engage the side folds of said opening bags, and a flanged folder to engage and form diamond folds in the bottoms of bags held by said carrier and engaged by said tuckers.

25. In bag machines, a moving carrier, a plurality of spaced sets of clamping devices mounted on said carrier to hold bags thereon, means to open the bottoms of bags held by said carrier, tuckers to engage the folds of said opening bag bottoms, means to engage and inwardly deflect the sides of said opening bag bottoms in advance of said tuckers and folding means to form the diamond folds in said bag bottoms while held by said carrier and engaged by said tuckers.

26. In bag machines, a moving carrier, a plurality of spaced sets of clamping devices mounted on said carrier to hold bags thereon, an opener roll co-operating with said carrier to open and hold in extended position the bottoms of bags held by said carrier while their middle portions are substantially yieldingly held out of direct contact with a support, tuckers to engage the folds of said opening bags and folder devices comprising deflectors to engage and inwardly deflect the free lateral edges of the diamond forming portions of said opening bag bottoms and a moving folder to engage and form diamond folds in said extended bag bottoms held by said carrier and engaged by said tuckers.

27. In bag machines, a carrier, means to hold bags upon said carrier, means to open the ends of said bags, deflector blades to engage and deflect inward the sides of said opening bag bottoms and a swinging folder plate provided with edge flanges mounted adjacent said deflectors to engage and form the diamond folds in said opened bag ends.

28. In bag machines, means to open the bag bottoms, stationary deflectors to engage and inwardly deflect the sides of said opening bag bottoms and a moving folder plate having edge flanges to engage and form diamond folds in said opened bag bottoms.

29. In bag machines, means to open bag

bottoms, deflector blades to engage and inwardly deflect the sides of the opening bag bottoms and a moving flanged folder to engage and form diamond folds in the opened bag bottoms.

30. In bag machines, means to open bag bottoms, stationary deflector blades to engage and inwardly deflect the sides and opening of said bag bottoms and a moving folder encircling said deflector blades to engage and form diamond folds in said opened bag bottoms.

31. In bag machines, a moving carrier, a plurality of spaced sets of clamping devices mounted on said carrier, said devices comprising carrier tuckers to engage the side folds of bags on said carrier, an opener co-operating with said carrier to open the bottoms of bags held thereby and aliners to engage and aline the folds of the opening bag bottoms prior to the engagement of said tuckers therewith.

32. In bag machines, a moving carrier, a plurality of spaced sets of clamping devices mounted on said carrier to hold bags thereon, an opener roll co-operating with said carrier to open and hold in extended position the bottoms of bags engaged by said carrier, deflectors to engage and inwardly deflect the portions of said opened bag bottoms in ad-

vance of said clamping devices and a folder moving on an axis substantially parallel to the axis of said carrier to engage and form diamond folds in said extended bag bottoms, said folder having an edge flange to engage and aline the lateral edges of the diamond folds.

33. In bag machines, a carrier, means to open and hold in extended position the bottoms of bags engaged by said carrier and a folder moving on an axis substantially parallel to the axis of said carrier to engage and form diamond folds in said extended bag bottoms, said folder having edge flanges to engage and aline the lateral edges of the diamond folds.

34. In bag machines, a carrier to feed forward forming bags, means to open and hold in extended position the bottoms of said bags, a folder and means to move said folder into contact with said extended bag bottoms in a direction substantially transverse to the plane of said extended bag bottoms to form diamond folds therein, said folder having edge flanges to engage and aline the lateral edges of the diamond folds.

WILLIAM LIDDELL.
